(57) CLAIM

The ornamental design for an waist playbook, as shown and described.

DESCRIPTION

FIG. 1 is a perspective view of an embodiment of a waist playbook in accordance with our new design.

FIG. 2 is a first side view thereof.

FIG. 3 is a second side view thereof.

FIG. 4 is a first edge view thereof.

FIG. 5 is a second edge view thereof.

FIG. 6 is a top plan view thereof.

FIG. 7 is a bottom plan view thereof.

FIG. 8 is a perspective view of the waist playbook of FIG. 1 being worn about a waistband.

FIG. 9 is a perspective view of the waist playbook of FIG. 1 being worn about a human waist.

FIG. 10 is an alternate view of the waist playbook of FIG. 1.

FIG. 11 is a perspective view of an embodiment of a waist playbook in accordance with our new design.

FIG. 12 is a first side view thereof.

FIG. 13 is a second side view thereof.

FIG. 14 is a first edge view thereof.

FIG. 15 is a second edge view thereof.

FIG. 16 is a top plan view thereof.

FIG. 17 is a bottom plan view thereof.

FIG. 18 is a perspective view of the waist playbook of FIG. 11 being worn about a waistband.

FIG. 19 is a perspective view of the waist playbook of FIG. 11 being worn about a human waist; and,

FIG. 20 is an alternate view of the waist playbook of FIG. 11.

The broken lines shown in the drawings depict portions of the waist playbook, which form no part of the claimed design. The broken lines in FIGS. 8, 9, 18 and 19 depict environmental structure of the waist playbook and form no part of the claimed design. In addition, the surface shading, if any, illustrated in the drawings is provided merely to highlight the contour of the design, it is not intended to be illustrative of texture or gloss.

1 Claim, 16 Drawing Sheets
